(73) Assignee: **Sony Corporation**, Tokyo (JP)

Primary Examiner—Kay H. Chin
(74) Attorney, Agent, or Firm—Rader, Fishman & Grauer PLLC

(**) Term: **14 Years**

(57) **CLAIM**

(21) Appl. No.: **29/161,126**

The ornamental design for a computer combined with recorder/player, as shown and described.

(22) Filed: **May 24, 2002**

DESCRIPTION

(51) LOC (7) Cl. **14-02**
(52) U.S. Cl. **D14/346**
(58) Field of Search D14/136, 341-346;
D18/1, 2, 7; 235/145 A, 145 R; 341/22,
23; 345/156, 168, 169, 172, 173, 87; 349/12;
361/680-686

FIG. 1 is a perspective view of a computer combined with recorder/player showing my new design;
FIG. 2 is a front elevational view thereof;
FIG. 3 is a left side elevational view thereof;
FIG. 4 is a right side elevational view thereof;
FIG. 5 is a top plan view thereof; and
FIG. 6 is a bottom plan view thereof; and,
FIG. 7 is a rear elevational view thereof.
FIG. 7 is for illustrative purpose only and forms no part of claimed design.

Portions in broken lines are for illustrative purpose only and form no part of claimed design.
